DESIGN FOR A BEAM AND POISE ASSEMBLY FOR A WEIGHING SCALE

Henry Dreyfuss, New York, N. Y., assignor to
Fairbanks, Morse & Co., Chicago, Ill., a corpo-
ration of Illinois

Application June 22, 1944, Serial No. 114,137

Term of patent 14 years

(Cl. D52—10)

To all whom it may concern:

Be it known that I, Henry Dreyfuss, a citizen of the United States, residing at New York city, in the county of New York and State of New York, have invented a new, original, and ornamental Design for a Beam and Poise Assembly for a Weighing Scale, of which the following is a specification, reference being had to the accompanying drawing, forming part thereof.

In the drawing

Fig. 1 is a top plan view of the beam and poise assembly for a weighing scale, showing my new design;

Fig. 2 is a front elevational view thereof;

Fig. 3 is a rear elevational view thereof;

Fig. 4 is an end view of the beam;

Fig. 5 is a sectional view of the beam taken at line 5—5 of Fig. 2, and

Fig. 6 is a sectional view of the beam taken at line 6—6 of Fig. 2.

In Figs. 2 and 3 the base of the beam and poise assembly is shown broken away, for convenience of illustration.

I claim:

The ornamental design for a beam and poise assembly for a weighing scale, as shown.

HENRY DREYFUSS.
